UNITED STATES PATENT OFFICE.

JOHN BURRY, OF RIDGEFIELD PARK, NEW JERSEY.

CIRCUIT-BREAKER.

SPECIFICATION forming part of Letters Patent No. 760,679, dated May 24, 1904.

Application filed August 30, 1902. Serial No. 121,550. (No model.)

To all whom it may concern:

Be it known that I, JOHN BURRY, a citizen of the United States, and a resident of Ridgefield Park, in the county of Bergen and State 5 of New Jersey, have invented a certain new and useful Improvement in Circuit-Breakers, of which the following is a specification.

This invention relates to transmitting apparatus for printing-telegraph systems, one 10 object of the invention being to operate both line and local circuits by means of a single trailer.

Other objects are to repeat characters, to prevent "kicking," to improve the general 15 operation of the transmitter, and to permit of certain adjustments and repairs to be easily made.

To these ends the invention consists of features of construction and combinations of devices 20 hereinafter described, and more particularly pointed out in the claims concluding this specification.

The preferred form of the invention is illustrated in the accompanying drawings, forming 25 part hereof, in which—

Figure 1 is a plan view of the apparatus. Fig. 2 is a plan view of the trailer and other parts under the top plate. Fig. 3 is a sectional view through the sunflower. Fig. 4 is 30 an end view of the trailer, and Figs. 5, 6, and 7 are views illustrating various positions and operations of the "repeating" devices.

In the drawings the reference *a* designates a base of, preferably, an insulating material. Above this base *a* is a top plate *b*, of 35 metal, screws *c*, and posts (not shown) connecting base and top plate. Between base and top plate and separated from both is a ring *d*, which is suspended from the top plate 40 by screws *e* and posts on the ring, all in a common manner.

f g are two sets of keys arranged in concentric circles and mounted to have endwise motion in the plates *b d*, said keys being 45 raised to normal positions by springs *h*. The keys of the inner ring *f* have platina tips or contacts at their lower ends.

The base *a* is bored through at a point in the axis of the circles *f g*, in which bore is a 50 flanged bushing *i*, which forms a bearing for

a shaft *k*. Below the bushing *i* the shaft *k* has a grooved pulley fast thereto, whereby the shaft is rotated by means of a cord *l*, which is guided by rollers *m*. Above the bushing *i* is a sleeve *n*, loose on the shaft *k*, and to 55 this sleeve *n* the trailer *o* is secured. The upper end of sleeve *n* is bored out for the reception of a friction-bushing *p*, which connects shaft *k* and sleeve *n*.

q is a screw for securing shaft *k*, sleeve *n*, 60 and bushing *p* together. Shaft *k* is stepped in a spring *r*, which may be swung aside at any time by removing one of the two screws which secure it in place.

Secured to base *a* and concentric with but 65 electrically insulated from bushing *i* is a sunflower *s*, whose alternate segments are electrically connected and the adjacent segments of which are electrically insulated from each other. 70

t is a split battery having one pole connected with one set of segments of the sunflower and the other pole connected with the other set of segments. The trailer *o* has a block or brush *u* mounted to slide vertically 75 in a slot therein to coat with the sunflower *s*, a spring *v* keeping the brush *u* in contact with the sunflower. The spring *r* is connected with or forms part of the line, as hereinafter described. The described arrangements provide 80 for the reversal of the line-current as block *u* slides from one to another segment of the sunflower.

From spring *r* the line-current passes to a post *w* and thence through springs *x y* to another post *w* and thence to line, where there are one or more receivers. The springs *x y* are so arranged and adjusted that they are in contact with each other when in normal position, as shown in Fig. 2. The spring *x* has 90 an armature *z* thereon, which armature is in front of the poles of an electromagnet 1, which forms part of a local circuit.

2 is a rheostat or adjustable resistance-box connected electrically with posts *w* to form a 95 shunt for the circuit-breaker *x y*.

The local circuit includes a metal ring 3, concentric with but electrically independent of the sunflower *s*, the keys *f*, plate *b*, magnet 1, a battery 4, connections, (the electric con- 100

nection furnished by the plate *b* is indicated in Fig. 2 by the dotted line *b*^x,) and the brush 5 and contact-plate 6, on but insulated from the trailer *o*. It will be noted that the local 5 circuit is open except when a key *f* is depressed and arrests the trailer *o* by contacting with plate 6.

The keys *g* when depressed are in the path of a stop-plate 7 on the trailer *o*, said stop- 10 plate being of insulating material or being insulated from the trailer, so that no current shall pass when the trailer is arrested by a key *g*.

R is a key having a conical bottom end so 15 placed that when springs *x* *y* are in normal position and this key is depressed it will force spring *y* away from spring *x* and break their contact, (see Fig. 7,) and when the contact between springs *x* *y* is broken when magnet 1 20 attracts armature *z*, thus leaving the parts as shown in Fig. 5, the depression of key *R* will force the springs *x* *y* together, Fig. 6, for springs *x* *y* are so tensioned as to cause spring *y* when magnet 1 draws spring *x* over to follow 25 low part of the way, so as to pass the point of key *R*.

The operation of the foregoing devices is as follows: The trailer *o* is drawn by a suitable motor through the shaft *k*, and its brush 30 *u* passes over and in contact with the sunflower *s*, continually reversing the line-current, as above stated, and while the brush 5 trails around on ring 3. When any one of the keys in row *f* is depressed, the trailer *o* 35 is arrested by the contact of plate 6 and the depressed key, which contact closes the local circuit and energizes the magnet 1. The energized magnet 1 attracts armature *z* and so moves spring *x* to the position thereof shown 40 in Fig. 5, thus breaking the contact of springs *x* *y* with each other and shunting the line-circuit through the rheostat, which almost opens the line. The receiver prints the character corresponding to the depressed key, and if it is desired 45 to repeat the printing of such character the key *R*, while the depressed key *f* is still held down, is also depressed as many times as it is desired to repeat the printing of such character, thus forcing spring *y* into contact with 50 spring *x* (see Fig. 6) an equal number of times. On the release of the depressed keys *f* and *R* the same are returned to normal position by their springs, and the friction-drive starts the trailer *o* again and springs *x* *y* return to their 55 normal positions. (See Fig. 2.) On depressing any key *g* the trailer *o* is arrested thereby

and the line-current is prolonged at full strength, since magnet *i* is not energized at this time and the line-current passes via the springs *x* *y* and the character corresponding 60 to the depressed key is printed by the receivers. Such character may be repeated by depressing key *R* as many times as it is desired to repeat, said key *R* at each depression forcing the springs *x* *y* apart, as shown in 65 Fig. 7, and so shunting the circuit through the rheostat, it being understood that the depressed key *g* is held down while such repeating is taking place. On the release of keys *g* *R* their springs return them to their normal 70 positions, trailer *o* starts up again, and springs *x* *y* return to normal position.

It is noted that the fiber or other sleeve *p* provides a simple, durable friction connection between shaft *r* and sleeve *n* and that it is 75 especially convenient in that when worn it may be removed and another similar sleeve be substituted by any one having a screw-driver—that is to say, this clutch can be adjusted and repaired by any one, so that a 80 skilled person is not required to be called to repair the apparatus when the clutch becomes worn. The amount of friction can be regulated by the screw within certain limits.

What I claim as new, and desire to secure 85 by Letters Patent of the United States, is—

1. In a transmitter, a line circuit-breaker consisting of two springs tensioned to press normally against each other, an electromagnet for operating one spring to open the circuit, 90 and a pointed key past whose point the other spring moves or is moved as the circuit is broken and made, whereby the circuit may be remade or be broken by operating said key.

2. In a transmitter, a line circuit-breaker 95 consisting of two springs tensioned to press normally against each other, an electromagnet for operating one spring to open the circuit, and a pointed key past whose point the other spring moves or is moved as the circuit is broken and made, whereby the circuit may be remade or be broken by operating said key, with a rheostat for shunting said circuit-breaker when it is opened.

Signed at New York city, in the county of 105 New York and State of New York, this 28th day of August, A. D. 1902.

JOHN BURRY.
